[57] CLAIM

The ornamental design for a mirror, as shown and described.

DESCRIPTION

FIG. 1 is a front perspective view of a mirror showing our new design;

FIG. 2 is a top plan view thereof;

FIG. 3 is a front elevational view thereof;

FIG. 4 is a side elevational view thereof, the opposite side being a mirror image thereof; and,

FIG. 5 is an enlarged sectional view taken along line A—A of FIG. 3.

The rear side of the mirror is unadorned.
